EMERGENCY TELEPHONE CALL AND
CIRCUIT THEREFOR

Joseph Palumbo, Bronx, N. Y.

Application May 1, 1945, Serial No. 591,274

5 Claims. (Cl. 179—81)

1

This invention relates to an improved telephone circuit and emergency signal control, and one of its objects is to provide a local customer station with means which will enable the central station to signal the customer when the receiver of the customer's station is disengaged from the supporting hook.

Another object of the invention is the provision of a telephone receiver with a switch arranged to be operated by supplying excess current to the magnetic windings of the receiver, and a signal bell which is energized at the customer station, when the receiver is supplied from a central control or switch with excess current.

With the above and other objects in view the invention relates to certain new and useful constructions, combinations, and arrangements of parts, clearly described in the following specification and fully illustrated in the accompanying drawings, in which:

Fig. 1 is a front elevation of the receiver, showing the cap removed to expose the pole ends of the magnets, the cap being broken away for convenience.

Fig. 2 is a similar view, enlarged, showing the circuit for the receiver and emergency bell.

Fig. 3 is a diagrammatic view of the complete telephone circuit.

Fig. 4 is a diagrammatic view of a modified telephone circuit.

Referring to the accompanying drawings, which illustrate the practical embodiment of my invention, 5 designates a telephone receiver, which is provided with a case 6 of insulating material, and electromagnets 7 and 8, which include pole ends 7' and 8', which are normally engaged by the usual soft iron diaphragm 9. This receiver is also provided with the usual retaining cap 10, which is screw threaded on the case 6.

A plate 11, in the form of a crescent shaped body is mounted around the magnets 7 and 8, by means of the binding screws 12 and 13, the ends of which project outwardly of the plate 11. The inner semi-circular edge 11a of the plate is spaced from the magnets 7 and 8. On the binding post or screw 12 an insulating block 14 is mounted, and is retained in position by a nut 15, which is threaded on the post or screw 12.

An insulating block 16 is pivotally mounted on the plate 11 by means of a pin 17, which extends through the block 16 between the ends thereof, and this pin pierces the plate 11 at its inner end, so that the inner edge 16a of the block 16 will be spaced out of contact with the magnets 7 and 8 and their pole ends 7' and 8'.

2

The pivoted block 16 is equipped with a lateral magnetic finger 18, which is designed to be normally spaced out of contact with the side of the pole end 7', and is further provided with another lateral magnetic finger 19, which is normally spaced out of contact with the pole end 8', by the pressure of a curved cantilever spring 20, which is secured at one end to the insulation block 14, while the other end has sliding engagement with a metal strip 21, which is mounted rigidly on the pivoted insulated block 16, this other end being slightly curled outwardly at 20a, so that the spring will engage the metal strip 21 with the minimum of friction. The curled inner end 20a of the cantilever spring bears on the metal strip 21 to one side of the pivot pin 17, so that the lateral magnetic fingers 18 and 19 will be held out of contact with the sides of the pole end 7' and 8'. It is understood that these pole ends project outwardly of the magnetic windings or coils, so that there is ample room for the swinging motion of the lateral magnetic fingers 18 and 19.

The metal strip 21 is extended outwardly of one end of the block 16 and is provided on one side with a contact element 21a, which is normally spaced out of contact with the stationary contact element 22, which is mounted on the crescent shaped plate 11, and is in electrical conducting connection with said plate 11.

30 The metal strip 21 is engaged by the end of a screw 23, which is threaded on an insulation block 24, mounted on the plate 11, which provides an adjustable stop for limiting the opening movement of the magnetic fingers 18 and 19.

35 The usual line wires 25 and 26 are connected to the windings of the magnets 7 and 8, with a current source or battery 27, and in circuit with the central station transmitter 28. The battery supply which normally flows through the magnets 7 and 8, to maintain the necessary talking circuit, is insufficient to generate enough magnetism in the magnets 7 and 8 to cause the projecting pole ends 7' and 8' to attract the lateral magnetic fingers 18 and 19, and as a result the pivoted switch block 16 and its metal strip 21 remain normally inoperative during the transmission of conversation over the talking circuit.

The resistance offered by the spring 20 to the pivotal movement of the block 16 and the strip 21, will be overcome by the charging of the magnets 7 and 8 with current in excess of the current used in normal operation. To accomplish this the spring 20 is connected to an additional circuit wire 29, at one end of the wire, and the other end of the wire is connected to the terminal

30 of the emergency bell 31. The other terminal 32 of this emergency signal bell is connected by the wire 33 with the wire 25, of the magnet 7. An additional current source or battery 34 is provided which has its negative side connected to the positive side of the current source or battery 27. The positive side of the additional battery 34 is connected to a manual switch 35 of the central station by a wire 36, and is further connected by a wire 37 with the line wire 26. This line wire 26 is also connected to the plate 11, by a nut 38, which is threaded on the binding screw or post 13.

When the receiver is disengaged from the usual supporting hook of the customer telephone set, 15 the usual calling bell circuit is broken, and it is then impossible for the central station, with existing equipment, to sound any sufficiently audible signal, to notify the customer that the receiver is not on its hook.

It frequently happens that a customer will remove the receiver from the hook of his set, for the purpose of making an outgoing call or connection, and will be called away from the telephone, without completing the connection, thus leaving the receiver off its hook.

Again a customer will be called to the telephone and will release the receiver while awaiting a delayed connection, or the end of an interruption, so that the receiver will remain for a considerable period of time from the supporting hook of its set.

Whenever a telephone receiver is thus disengaged from the receiver hook of its set, that particular customer telephone set is virtually isolated from the entire field telephone system, and it is impossible for any person calling the isolated telephone to make connections to either signal the customer or to engage in conversation.

In Fig. 3 I show a complete telephone circuit, and referring to this figure a receiver hook is indicated at 40, pivoting at 40a. The line wire 26 is connected to this hook. One wire 41 of a standard call bell 42 is connected to a contact element 41a, which is engaged by the hook 40 when the receiver is mounted on it or the hook is otherwise depressed. The other wire 43 of the call bell is connected to the line return wire 25, which is also connected to a primary coil 44. A secondary winding or coil 45 is connected by a wire 46 with a contact element 46a; which is engaged by the hook 40 when the hook is in its raised position, and the hook in this position also engages the contact element 26a of the line wire 26.

When the subscriber's or customer's station is called, current flows from the positive side of battery 27 through the line wire 26, through the central station switch 26a, through the central station transmitter 28, to the receiver hook 40, to contact 41a of wire 41, and through this wire to the call bell 42, and then by return wire 43 to the return wire 25 back to the battery 27, at the negative side thereof.

When the subscriber removes the receiver from the hook, the circuit through the call bell is broken, in the usual manner, by the hook being forced upwardly by its spring, and electrical connection is thereby established between the hook 40 and the contacts 26a of the line wire 26 and 46a of a wire 46. Current will now flow from the battery 27 to the receiver 5, to the primary winding 44 to the return wire 25 back to the negative side of the battery 27. At the same time current will flow from the contact 46a, through the wire 46, through the secondary winding 45,

to subscriber's transmitter 47, to wire 48, and thence through wire 25 to the negative side of the battery 27.

Due to the fact that the energy of the battery 27 is only sufficient to operate the call bell, or the subscriber's receiver and transmitter, and associated units of the included system, the emergency signal bell 31 will remain inactive during normal conversation use of the telephone. But should the subscriber fail to restore the receiver to its hook, at the end of the conversation, or leave the receiver off its hook for an indefinite period of time, then the central station operator can close switch 35, thereby causing current to flow from both batteries 27 and 34, which are connected to each other by the union line 34', through the wire 37 to line 26, thereby by-passing the central station transmitter 28 and its switch 26a.

The excessive current supply will now flow from line 26 to the hook 40, and thence through the wires 25 and 26 in the manner above described. But due to the greater voltage of the current supplied by both batteries 27 and 34 the energy of the magnets 7 and 8 will be sufficient to attract the magnetic fingers or armatures 18 and 19, and the switch strip 21 will close the circuit with contact 22, and current will then flow from the wire 26 to the wire 37 to the binding post 13, to the metal plate 11a, mounted on the plate 11, to contact 22, to contact 21a, to switch strip 21, to spring 20, through auxiliary wire 29 to the emergency bell 31, and thence by wire 33 to return wire 25, and to the negative side of battery 27.

The auxiliary battery 34 is, therefore, never utilized except to operate the emergency signal bell 31, and the circuit through this bell is closed by supplying an excessive amount of current or a higher voltage current supply to the receiver circuit, which thereby causes the receiver magnets to attract the armature fingers 18 and 19, and to close the circuit through the emergency bell 31, thereby calling the subscriber to the telephone.

In Fig. 4 I show a modified telephone circuit, 45 wherein an emergency bell is dispensed with, and the emergency call is made through the standard call bell 42. In this circuit arrangement the intermediate wire 29x from the receiver 5 is connected to a wire 41x at one end of the call bell 42, a wire 43x being connected to the line wire 25. A wire 29s is provided with a voltage switch 29s, which is normally inactive. But when the switch 35 is closed, and current from both batteries 27 and 34 is caused to flow through the feed wire 26, then the voltage switch 29s will close the line 29x, and current will flow to the call bell 42, thereby signalling the subscriber to respond.

The voltage switch 29s is constructed to operate only with the voltage current of both batteries, but when it does close the line 29x and thereby energizes the call bell, the sound thus generated by the call bell will be of greater volume or intensity than would normally be produced, so that the subscriber would be thus signalled that his receiver was off its hook.

It is understood that various materials may be used in the construction of the parts, and that various changes and adjustments may be made in the detail construction of the parts, their combination and arrangement, all within the scope of the invention, as defined by the claims herein set forth.

Having described my invention, I claim as new:

1. The combination with a telephone receiver

75 having a calling circuit and a calling bell ener-

gized thereby and a talking circuit with a switch operated by the withdrawal of the receiver therefrom, of means for supplying current to the calling circuit to energize the calling bell or to the talking circuit when the receiver is disengaged from said switch, and connections between the calling circuit and the talking circuit for energizing the calling bell when the receiver is disengaged from the said switch, said connections including means for supplying excess current to said talking circuit and a switch arranged to close the calling circuit when said excess current is supplied to the talking circuit.

2. The combination with a telephone receiver having a sound wave generating diaphragm and electro-magnets for acting on said diaphragm, a talking circuit for said electro-magnets, a calling circuit including a calling bell, a switch operated by the weight of the receiver for closing and opening said circuit last named, an emergency signal bell in circuit with the talking circuit, a switch operable by the electro-magnets of the receiver for controlling the circuit of the emergency signal bell, and means for supplying excess current to the talking circuit to increase the energy of the electro-magnets of the receiver, whereby said last-named switch will close the circuit of said emergency signal bell to permit the calling of the subscriber when said first-named switch is in open position with reference to the calling circuit.

3. A telephone receiver having electro-magnets provided with projecting pole ends and pole faces, a diaphragm responsive to the pole faces, a talking circuit for said electro-magnets, a normally inactive emergency signal included in said circuit, and a switch having a magnetic finger armature attractable by one of the magnet pole ends to close the circuit through the emergency signal when said talking circuit is supplied with current in excess of the current supply normally used to maintain the talking circuit active.

4. A telephone receiver having a pair of electro-magnets with exposed pole ends, a switch arm pivoted adjacent to the magnets and provided

5

with spaced magnetic finger armatures adapted to be attracted by the sides of the pole ends, a spring for holding said finger armatures normally spaced from the pole ends, a switch contact engageable by the switch arm when said finger armatures are actuated, a talking circuit for said magnets, an emergency signal bell having one terminal in circuit with one wire of the talking circuit and the other terminal connected with the switch arm, and means for supplying current to said talking circuit in excess of that required to maintain the talking circuit active, whereby the magnets will be supplied with excess energy and the finger armatures will be attracted to close the circuit through the emergency signal bell.

5. A telephone receiver provided with a calling circuit and a talking circuit, a switch engageable by the receiver for holding the talking circuit normally open and the calling circuit closeable at a distant point, an emergency signal bell having connections with the talking circuit and adapted to be inactive when said talking circuit is active, means for charging the talking circuit with a current supply in excess of that required to maintain the talking circuit service active, and means carried by the receiver for rendering the said connections for the emergency signal bell operative when the talking circuit is supplied with such excess current supply.

JOSEPH PALUMBO.
